UNITED STATES PATENT OFFICE.

WILLIAM C. HAZLETON, OF DELAWARE, OHIO.

CEMENT-BLOCK-TAMPING MACHINE.

1,120,383.

Specification of Letters Patent.

Patented Dec. 8, 1914.

Application filed December 31, 1912. Serial No. 739,503.

To all whom it may concern:

Be it known that I, WILLIAM C. HAZLETON, a citizen of the United States, residing at Delaware, in the county of Delaware and State of Ohio, have invented certain new and useful Improvements in Cement-Block-Tamping Machines, of which the following is a specification, reference being had thereto to the accompanying drawing.

10 This invention relates to plastic block tamping machines and has for its object the production of an efficient machine for packing the cement within the mold so as to cause the plastic material to mold in a solid body without having any porous portions formed therein.

Another object of this invention is the production of an efficient machine which consists of a minimum number of parts and 20 is efficient in operation.

With these and other objects in view, this invention consists of certain novel constructions, combinations and arrangements of parts, as will be hereinafter fully described 25 and claimed.

In the drawings:—Figure 1 is a side elevation of the machine. Fig. 2 is a front view thereof. Fig. 3 is a central vertical section of the machine. Fig. 4 is a section 30 taken on line 4—4 of Fig. 1. Fig. 5 is a section taken on line 5—5 of Fig. 1. Fig. 6 is a section taken on line 6—6 of Fig. 2. Fig. 7 is a vertical section through the swinging feet, showing the connections therefor. Fig. 35 8 is a top plan view of the swinging feet, as indicated in Fig. 7.

By referring to the drawings by numerals it will be seen that the device is hung from supporting beams 1 and comprises a frame 40 constituting a pair of depending side members 2. These depending side members 2 are braced by means of diagonally extending braces 3 and upon these side members 2 is journaled an operating or driving shaft 4. 45 This driving shaft 4 carries a drive pulley 5 which is driven by means of a belt 6 or any suitable driving means, and a clutch jaw 7 is fixedly secured to this shaft 4. A segmental gear 8 is slidably mounted upon

50 the shaft 4 and is provided with a collar 9 which collar is adapted to be engaged by the clutch finger 10 supported upon the transversely extending base bar 11 of the supporting frame. This clutch finger 10 is 55 engaged by means of a shifting rod 12 which rod passes through a journal 13. The outer

end of the rod 12 is provided with an angularly extending portion 14 for facilitating the sliding of the rod 12 within the journal 13. A coil spring 15 is employed and secured at its respective ends to the finger 10 and the frame 2 so as to normally hold the gear 8 out of mesh with the rack 16 hereinafter described. It will be seen that as the rod 12 is forced inwardly, the gear 8 will 60 be forced in engagement with the rack 16 thereby allowing the gear to operate or raise the plunger frame supporting the rack 16. 65

A transversely extending bracing bar 17 is interposed between the depending members 2 of the frame, as illustrated in Fig. 2, and through this bar or member 17 and the member 11 is slidably mounted the plunger frame 18 which plunger frame comprises a pair of vertically extending rods 19 which 70 rods are connected by means of a transversely extending member 20 at their upper ends. A rack supporting bar 21 is secured centrally of the transversely extending member 20 and is held in parallel relation 75 relative to the connecting bars 22 by means of a roller 23 which roller 23 is supported by means of a shaft 24. This shaft 24 has its respective ends journaled in the blocks 25 supported by these members 22. A rack bar 80 85 16, as previously described, is carried by the rack supporting bar 21 and fits in a cut-out portion 26 formed upon the inner face thereof. It will, therefore, be seen that the rack bar supporting member 21 will be held 90 in place between the segmental gear 8 and the roller 23. The rack supporting member or bar 21 is provided at its lower end with a transversely extending bar 27 to which bar 27 is clamped one of the tamping feet 28 95 by means of the clamp 29. These tamping feet are supported by means of the T-shaped connectors 30 which T-shaped connectors 30 are engaged by the connecting clips 31 having their threaded ends 32 threaded in the 100 T-shaped connectors 30 as indicated in Fig. 3. The flattened portions 33 of the clips 31 are secured to the upper faces of the tamping foot 28 by means of the bolts 34.

The rods 19 of the frame 18 carry T- 105 shaped joints 35 which joints support the rods 36 upon which rods are journaled the sleeves of the T-shaped supporting joints 37 of the swinging tamping feet. The T-shaped supporting joint 38 of the foot 28 110 is supported upon this rod 36. The lower ends of the rods 19 engage T-shaped con-

nectors 39 which connectors are provided with the usual clips 31 as described with reference to the foot 28 for connecting the feet 40 to the lower ends of the rods 19.

5 The swinging feet 41 are connected to the bars 42 similar to the manner in which the feet 40 are connected to the rods 19, and the T-shaped members 37 are so mounted upon the supporting rod 36 as to be swung out of 10 position. A handle 43 is connected to the swinging feet 41 so as to allow the swinging feet to be swung up out of position from between the stationary feet 40 and the central foot 28. These swinging feet may be 15 thrown to the position as shown in dotted lines in Fig. 1 when it is not desired or necessary to use them. Strap members 44 span the swinging feet as illustrated in Fig. 6 and are adapted to limit the swinging of 20 the feet in one direction. The transversely extending bar 27 is held in engagement with the rods 19 by means of the securing clips 45 as illustrated in Fig. 6.

A hand lifting lever 46 is pivotally secured to a vertical beam 47 as illustrated in Fig. 1 and to this hand lifting lever 46 is connected the cable 48 which is connected to the vertical sliding frame 18 after passing over a block 49. It will, therefore, be 25 seen that the feet 28, 40 and 41 may be lifted out of place by hand when it is not desired to operate the shaft 4 by means of the pulley wheel 5.

From the foregoing description it will be 30 seen that a very efficient and easy operated device has been produced whereby the sliding frame may be easily controlled in order to allow the plastic material within the mold to be thoroughly compressed by means 35 of the hammering of the feet 28, 40 and 41 upon the plastic material within the mold.

As will be seen in Fig. 3, the segmental gear 8 is provided with a blank portion 8^a 40 which will cause the sliding frame to drop after each half revolution of the segmental gear 8. This will cause a reciprocating motion of the frame 18 thereby constituting an efficient packing means. Of course, when it 45 is not desired to have the frame 18 reciprocate in this manner the clutch finger 10 may be so thrown as to draw the segmental gear 8 out of engagement with the rack bar 16 thereby allowing the shaft 4 to easily rotate 50 without causing the reciprocation of the frame 18.

Coil springs 50 are connected at their lowered ends to the transversely extending member 11 of the frame and have their upper ends engaging the upper end of the bar 60 21 so as to normally exert a downward pressure upon the sliding frame 18. These springs are of sufficient strength to cause the desired pressure to be brought to bear upon the plastic material contained within 65 the brace or mold with which the device is to be used.

A protector plate 51 is secured to the rear face of the rack supporting member or bar 21 so as to constitute a track for the roller 70 23 as illustrated in Fig. 3.

Having thus described the invention, what is claimed as new, is:

1. A device of the class described comprising a main frame, a reciprocating frame 75 comprising a pair of side bars, a T-shaped joint connected near the lower end of said side members, stub shafts engaging said T-shaped joints, a T-shaped joint connecting the adjacent ends of said stub shafts, a pipe section depending from said last mentioned T-shaped joint, a stationary foot supported or suspended from the lower end of said pipe section, pipe sections extending from the lower ends of said side members, stationary feet secured to the lower end of said last mentioned pipe sections, and swinging feet journaled upon said transversely extending stub shafts and adapted to be swung out of engagement with said 80 stationary feet.

2. A device of the class described comprising a reciprocating frame, stationary feet carried by said frame, a transversely extending supporting shaft carried by said frame, swinging feet supported upon said shaft, each foot comprising a body, clips secured to said body, joints connecting said clips, means for connecting said feet to said transversely extending bar, a lifting handle 100 connecting said swinging feet together, and transversely extending braces secured to said stationary feet and adapted to overhang said swinging feet for limiting the swinging movement of said swinging feet 105 in one direction.

In testimony whereof I hereunto affix my signature in presence of two witnesses.

WILLIAM C. HAZLETON.
